CLAIM

The ornamental design for a fishing reel protective case, as shown and described.

DESCRIPTION

FIG. 1 is a perspective view of my fishing reel protective case showing a fishing rod and line in phantom; FIG. 2 is a top plan view of my fishing reel protective case;

FIG. 3 is a front elevational view of my fishing reel protective case showing a latch and a cutout for a fishing reel shank;

FIG. 4 is a left side elevational view of my fishing reel protective case showing a hinge;

FIG. 5 is a rear elevational view of my fishing reel protective case showing a hinge;

FIG. 6 is a right side elevational view of my fishing reel protective case showing a hinge;

FIG. 7 is a bottom plan view of my fishing reel protective case; and

FIG. 8 is a perspective view of my fishing reel protective case in an open position showing in detail the design features of the hinges and latch.

The broken lines in FIG. 1 are for illustration purposes only and form no part of the claimed design.

FIG. 2.

FIG. 1.

FIG. 3.

FIG. 4.

FIG. 5.

FIG. 6.

FIG. 7.

FIG. 8.
